[57] CLAIM

The ornamental design for a faceplate of a rotary switch housing, as shown and described.

DESCRIPTION

FIG. 1 is a perspective view of the housing for a faceplate for a rotary switch housing highlighting our new design; FIG. 2 is a top plan view of the faceplate for a rotary switch housing of FIG. 1;

FIG. 3 is a side elevational view of the faceplate for a rotary switch housing in FIG. 1;

FIG. 4 is a bottom plan view of the faceplate for a rotary switch housing of FIG. 1; and,

FIG. 5 is an end view of the faceplate for a rotary switch housing of FIG. 1.

The broken lines showing a switch housing is for illustrative purposes only, and forms no part of the claimed design.
